UNITED STATES PATENT OFFICE

GEORGE WESP, OF NEW YORK, N. Y., ASSIGNOR TO THE ROSENTHAL CHINA CORPORATION, OF NEW YORK, N. Y., A CORPORATION OF NEW YORK

DESIGN FOR A PLATE OR SIMILAR ARTICLE

Application filed June 8, 1931. Serial No. 40,129. Term of patent 7 years.

To all whom it may concern:

Be it known that I, GEORGE WESP, a citizen of Germany, and an applicant for citizenship of the United States, residing in New York, county and State of New York, have invented a new, original, and ornamental Design for Plate or Similar Article, of which the following is a specification, reference being had to the accompanying drawing, forming a part thereof.

The figure is a top plan view of a plate, showing my new design. The ornamentation shown is continued throughout the surface of the plate.

I claim:

The ornamental design for a plate or similar article as shown and described.

GEORGE WESP.
